United States Patent Office.

SENECA M. RICHARDSON, OF WORCESTER, MASSACHUSETTS.

Letters Patent No. 60,787, dated January 1, 1867.

IMPROVEMENT IN PLANING-MACHINES.

The Schedule referred to in these Letters Patent and making part of the same.

TO ALL WHOM IT MAY CONCERN:

Be it known that I, SENECA M. RICHARDSON, of the city and county of Worcester, and Commonwealth of Massachusetts, have invented new and useful Improvements in Planing, Tonguing, and Grooving-Machines; and I do hereby declare that the following is a full, clear, and exact description of the same, reference being had to the accompanying drawings, forming a part of this specification, in which—

Figure 1 represents so much of a tonguing and grooving machine as is necessary to illustrate my invention.

Figure 2 represents a top or plan view of the parts shown in fig. 1; and

Figure 3 represents a plan view of a detached part.

The nature of my invention consists of a peculiarly operating mouth-piece or pressure-surface to be used in connection with the cutting cylinders of either a planing or tonguing and grooving-machine.

In the drawings, A is the tonguing and grooving-head to which the cutters B are fastened. Head A is fastened to the top of the shaft, C, which is supported and turns in boxes or bearings, D, the lower one only being shown in the drawings. Shaft C and head A, with its cutters, are driven by a belt running upon pulley, E, from any convenient driving-shaft, drum, or pulley. F is the bed-piece, over which the boards or planks are fed to the cutters in the ordinary manner by feed-rolls. G is a self-adjusting mouth-piece or presser, which is so connected or attached to the bed-piece, as to always retain the same relative position to the cutters and cutter-head, that is, it always remains or works the same distance from the centre of the shaft upon which the cutter-head works. The face I of the mouth-piece is attached to a circular part, J, which has two circular grooves 1 and 2 cut in it, as shown at fig. 3, in which the mouth-piece is shown with the cap K removed. In each of these grooves is placed a friction-roll, 3. A curved groove is cut in the top of the bed-piece F to receive a spiral spring, 4, one end of which rests against a stop or lug fast to the curved part J, and the other end against the bed-piece at the end of the groove. The parts are put together as follows: Spring 4 is placed in the groove or recess cut in the bed-piece, after which the mouth-piece is placed so that the rear end of the circular part J will be over the spiral spring as shown in the drawings. The friction-rolls 3 are now inserted in the grooves 1 and 2, as shown, and then cap K placed in position and the screws or bolts 5 passed down through the cap and friction-rolls 3, into the bed-piece F. It will be seen that the mouth-piece thus attached is free to spring back when sufficient force is applied to its face or presser part I, to overcome the force of spring 4, and that as soon as the pressure is removed spring 4 will cause it to return or spring back to its original position, as shown in fig. 3. L is an adjustable guide, attached to the top of the bed F, against which one edge of the plank or board slides and by the latter is kept in proper position while passing through the machine. The principal object of my invention is to prevent the fibres of the wood being split or torn up by the action of the cutters and which is apt to be the case where no pressure-bars are used. My pressure-bar or mouth-piece is so constructed that it always retains the same relative position to the cutters, and hence there is a uniformity and accuracy in the work not accomplished by those machines which have pressure-bars or mouth-pieces; but which move away from the cutters or cutter-head when forced back by the uneven surface of the board or plank. I have shown my invention applied to a tonguing and grooving-machine, but it is alike applicable to a planing-machine.

Having described one good way in which my invention may be applied to practical use, what I claim as my invention, and desire to secure by Letters Patent, is—

In a tonguing and grooving or other like machine, I claim the combination with the cutter-head of an adjustable mouth-piece or presser-bar attached to the bed-piece of the machine, so that while separate and distinct from the cutter-head, it may be capable of moving concentrically therewith, the whole being constructed and arranged for operation, substantially as shown and described.

SENECA M. RICHARDSON.
